PIPETTE STORAGE RACK

David E. Berg, 3326 S. 78th St., Omaha, Nebr. 68124

Filed Oct. 15, 1970, Ser. No. 25,499

Term of patent 14 years

Int. Cl. D24—02; D6—99

U.S. Cl. D16—1

FIG. 1

FIG. 2

FIG. 3

FIG. 4

FIG. 5

FIG. 6

FIG. 1 is a perspective view of the pipette storage rack showing my new design;

FIG. 2 is a right end view thereof, wherein the left end view is a mirror image thereof;

FIG. 3 is a rear elevational view thereof;

FIG. 4 is a top plan view thereof;

FIG. 5 is a bottom plan view thereof; and

FIG. 6 is a sectional view along the lines 6—6 in FIG. 4.

I claim:

The ornamental design for a pipette storage rack, substantially as shown and described.
